Primary Examiner — Keli L Hill

(57) **CLAIM**

The ornamental design for a comb set, as shown and described.

DESCRIPTION

1.1 is a front view of a comb set showing my new design;

1.2 is a back view thereof;

1.3 is a left view thereof;

1.4 is a right view thereof;

1.5 is a top side view thereof;

1.6 is a bottom view thereof;

1.7 is a perspective view thereof; and

1.8 is an exploded view thereof.

The broken lines in the drawing depict portions of the comb set that form no part of the claimed design.

1 Claim, 8 Drawing Sheets(56)
